HAY BALER

Constantine J. Kermes, Ephrata, and Edwin B. Nolt,
James W. McDuffie, and Otto W. Luek, New Holland,
Pa., assignors to Sperry Rand Corporation, New Hol-
land, Pa., a corporation of Delaware

Application May 20, 1957, Serial No. 46,240

Term of patent 14 years

(Cl. D40—1)

Fig. 1.

Fig. 2.

Fig. 3.

Fig. 4.

Fig. 1 is a left-front perspective view of a hay baler embodying our new design; and,

Figs. 2, 3, and 4 are right-front, left-rear, and left-side perspective views, respectively, of the baler.

We claim:

The ornamental design for a hay baler, as shown.
